UNITED STATES PATENT OFFICE.

GEORGE WIEGAND, OF BERLIN, ONTARIO, CANADA.

DESIGN FOR A BOTTLE.

48,212.

Specification for Design.

Patented Nov. 23, 1915.

Application filed April 27, 1915. Serial No. 24,368. Term of patent 7 years.

To all whom it may concern:

Be it known that I, GEORGE WIEGAND, a subject of the King of Great Britain, residing at Berlin, in the Province of Ontario and Dominion of Canada, have invented a new, original, and ornamental Design for Bottles, of which the following is a specification, reference being had to the accompanying drawing, forming a part thereof.

The figure is a perspective view of a bottle, showing my new design.

I claim:

The ornamental design for a bottle, as shown.

GEORGE WIEGAND.
